UNITED STATES PATENT OFFICE.

GEORGE W. CLARK, OF OAK PARK, ILLINOIS.

COMBINED COAL AND GAS RANGE.

1,301,906.

Specification of Letters Patent. Patented Apr. 29, 1919.

Application filed July 9, 1917. Serial No. 179,520.

To all whom it may concern:

Be it known that I, GEORGE W. CLARK, a citizen of the United States, residing at Oak Park, county of Cook, State of Illinois, have 5 invented a certain new and useful Improvement in Combined Coal and Gas Ranges, and declare the following to be a full, clear, and exact description of the same, such as will enable others skilled in the art to which 10 it pertains to make and use the same, reference being had to the accompanying drawings, which form a part of this specification.

My invention has for its object to produce a combined coal and gas range which, without 15 requiring the user to remove or replace any parts when changing from one kind of fuel to the other, shall be as efficient, so far as the oven is concerned, as any coal range and, when burning gaseous fuel, shall possess a maximum efficiency as a gas range.

A further object of my invention is to produce a gas burning arrangement for ovens which will permit the flame to be turned very low without danger that it will 25 be blown out or shoot back to the air inlet end of the burner when the oven door is opened or for any other cause.

The various features of novelty whereby my invention is characterized will herein- 30 after be pointed out with particularity in the claims; but, for a full understanding of my invention and of its objects and advantages, reference may be had to the following detailed description taken in connection with 35 the accompanying drawings, wherein:

Figure 1 is a vertical section through a range constructed in accordance with the present invention on a plane parallel with the front and back of the range;

Fig. 2 is a section taken approximately on line 2—2 of Fig. 1; and

Fig. 3 is a section taken approximately on line 3—3 of Fig. 2.

Referring to the drawings, 1 represents 45 the oven of any usual or suitable coal range. At two opposed sides, that is at the side adjacent to the ashpit and at the opposite side and adjacent to the bottom of the oven, are arranged small prostrate tunnels or flues, 50 2 and 3, which preferably lie outside of the planes of the inner faces of the two side walls of the oven in order not to decrease the width of the oven. These tunnels or flues may conveniently be formed by caus- 55 ing the main castings which form the walls of the oven to bulge outwardly, the inner

walls of the tunnels or flues being formed by plates, 4, whose lower edges are spaced apart from the bottom wall of the oven to provide long slots or passages through which 60 the flame and hot gases may be projected. In each tunnel is a burner, 5, which may be a simple tubular member extending from one end of the tunnel to the other and provided with a series of orifices or outlets, 6, 65 so disposed that the flame from one burner will be directed toward the other burner through the flame slot or outlet. The orifices in the burner may be so disposed that the flames will extend horizontally or else they 70 may be caused to incline either upwardly or downwardly.

Each of the cover plates, 4, is preferably provided with a lip or flange 7, which overhangs the corresponding burner in 75 such a way as to shield it against dripping or splashing grease or other material. At the rear end of the oven the tunnels 2 and 3 communicate with a pair of tunnels, 8 and 9, extending along the rear of the 80 oven and preferably outside thereof from the tunnels or flues 2 and 3 through the back smoke flue 10, and terminating in communication with an air chamber, 11, extending through the back smoke flue. 85 Supply pipes, 12, 12, extend through the tunnels or flues 8 and 9 and are joined to the rear ends of the burners, the supply pipes being connected to and leading from a head, 13, arranged within an air chamber, 11. The 90 member 13 is provided with the usual air inlet ports, 14, in an adjustable valve or head, 15. Gas is supplied through a pipe, 16, ending in a nipple or nozzle, 17, which enters the member 13 axially of the latter. These 95 parts may of course take any usual or suitable construction as the particular details illustrated are simply those of a well known device for admitting gas to a burner or burners and at the same time drawing in air to 100 mingle with the gas before it is discharged through the burner outlets. The front of the air chamber 11 is closed by the rear wall of the oven while at the sides and at the top and bottom the air chamber is completely surrounded by the main smoke flue. The back of the air chamber is formed by or has arranged therein a movable door, 18, which may conveniently be hinged at the top as indicated at 19 so that it will normally close 105 by gravity. When the door is closed, communication between the chamber 11 and the

outside atmosphere is interrupted and consequently there can be no flow of air in either direction between the oven and the outside atmosphere through the flues or tunnels connecting the oven and the chamber, 11, and, since the mixing head, 13, is arranged wholly within the chamber 11, no air can flow into or out of the oven through the burners when the door, 18, is closed.

- 10 For the purpose of permitting the escape of the combustion gases I have formed discharge outlets in the bottom of the oven through which the gases may escape into the usual smoke flue 20 underlying the oven.
- 15 There are preferably a series of these openings, 21, arranged in a row midway between and parallel with the burners and extending from the front to the rear of the oven. The openings, 21, are preferably arranged in the bottom of a depression, 22, within which lies a valve or damper, 23, in the form of a slide provided with perforations, 24, equal in number and spacing to the openings 21. The damper is somewhat shorter than the recess 22 so that it may be moved from a position in which the two sets of holes register with each other to a position in which the holes 21 are covered by a solid portion of the damper or slide.
- 20 If desired, an auxiliary slide, 25, may be placed on the under side of the oven wall below the damper; the slide 25 being connected to the damper so as to be movable therewith, and taking the form of a comb the teeth or fingers of which will serve to shear or scrape off any masses of soot which might tend to collect underneath the bottom wall of the oven around the discharge openings therein.
- 25 The oven damper, the air controlling door, and the gas valve may be controlled in any suitable way but I prefer to connect them all together so that they will move in unison so that the amount of gas, the amount of air, and the effective size of the discharge outlet for the combustion products will vary one with the other so that there will always be maintained the proper relation between them and, whenever the gas is turned off, 30 the oven will be sealed against the entrance of air thereto or its escape therefrom. To this end I have connected to the rear end of the damper, 23, an actuating member, 26, which extends through the rear wall of the oven into the chamber 11. At the rear end of the member 26 is a finger, 27, which engages with the door 18 and swings it open as the damper is moved into its open position; the parts being so proportioned that when 35 the damper 23 is closed the door 18 will also be closed. The member 26 is also provided with rack teeth, 28, adapted to be engaged by the teeth of a gear segment, 29, on a shaft, 30, extending along the rear of the range. At one side of the range is a rota-

table operating rod, 31, having a handle, 32, at the front end. The rear end of the operating rod is connected to the movable member, 33, of a valve in the gas supply pipe 16. A bevel gear segment, 34, on the rod or 70 shaft, 31, meshes with a complementary segmental tooth member, 35, on the shaft 30; whereby, when the handle 32 is turned, the gas valve, the damper and the air controlling door are operated simultaneously. As 75 heretofore stated, the parts are so proportioned that when the gas is turned off the air door will be closed and the damper will also be closed and, when the gas is turned on, the air door and the damper are opened to the 80 proper degree to furnish the requisite amount of air both into the interior of the burners and through the burner tunnels or flues, and an outlet for the escape of the combustion products best suited for the particular conditions then existing.

The outlet openings or orifices in the burners may be graduated in size from the rear of the oven toward the front, so that no matter how little gas is flowing, it will always 90 be properly distributed throughout the length of the burners.

It will be seen that all of the air which enters the oven for the purpose of sustaining combustion, whether it passes through the 95 burners or through the burner tunnels or flues, enters at the hottest point, namely through the main back smoke flue, and is thus preheated; this being particularly true of the air which flows through the tunnels or flues 8 and 9 and then through the tunnels or flues 2 and 3 and down over the burners in order there to mingle with the gas flames. Thus, efficient combustion results and because the products of combustion 100 flow evenly from the burner flues or tunnels to the center of the oven, an even distribution of heat across the entire oven is economically effected. It is not necessary to provide means for carrying any of the combustion gases into the upper regions of the oven because no cool air or other gaseous fluid can remain in the upper regions of the oven as it will always be displaced by ascending hotter gaseous fluids. It is therefore possible to bake or roast at any desired 110 elevation in the oven.

The automatic control of the air and gas, not only the main supply of air, but also that entering the burners through the mixing head, is a very important feature because it, for the first time, so far as I am aware, so regulates all of the air and the gas that the flame may be turned very low without danger that it will be blown out or will 120 be carried back into the mixing head when the oven door is open; making it possible to avoid waste through the use of a higher flame than is necessary for the maintenance 125 of the proper temperature in the oven sim- 130

ply for the purpose of insuring that the burner will remain properly lighted at all times; because with my improved method of regulation, the flame need at no time be 5 any higher than is necessary to produce the required number of heat units for the maintenance of a given temperature in the oven. It will thus be seen that I have produced 10 a simple construction which leaves the coal range unimpaired when coal is being burned as a fuel, provides for efficient baking or roasting by using gas as a fuel, and requires no parts to be removed or replaced in order to transform the range from a coal burning 15 range to a gas burning range. The elimination of all parts which must be removed or replaced has not only the result of making the range extremely convenient, but because there are no baffle plates or other devices for 20 confining and directing or deflecting the flames and combustion gases, there is no interference with the free and even distribution of heat and therefore much better results are obtained when gas is being burned 25 than are possible in ranges which obstruct or interfere with the free distribution of heat by means of baffle plates or the like.

While I have referred to coal as one of the two fuels, it will of course be understood 30 that instead of coal any other suitable fuel may be employed. Furthermore, while I have illustrated and described with particularity only a single preferred form of my invention, I do not desire to be limited to 35 the exact structural details thus illustrated and described; but intend to cover all forms and arrangements which come within the terms employed in the definitions of my invention constituting the appended claims.

40 I claim:

1. In combination with a coal range having an oven, a smoke flue underlying the oven and a back smoke flue; auxiliary flues lying at opposite sides of the oven and communicating therewith through long slots or openings adjacent to the bottom of the oven; burners in said auxiliary flues, an air passage extending through the back smoke flue and communicating with said auxiliary flues, means including an air mixing device arranged in said passage for supplying fuel to said burners, and a damper controlled smoke outlet extending through the bottom of the oven into the smoke flue underlying 55 the oven.

2. In combination with a coal range having an oven, a smoke flue underlying the oven and a back smoke flue; auxiliary flues lying at opposite sides of the oven and communicating therewith through long slots or openings adjacent to the bottom of the oven; burners in said auxiliary flues, an air passage extending through the back smoke flue and communicating with said auxiliary flues, means including an air mixing device

arranged in said passage for supplying fuel to said burners, a movable closure for said passage, and a damper controlled smoke outlet extending through the bottom of the oven into the smoke flue underlying the oven. 70

3. The combination with a coal range having an oven, a smoke flue underlying the oven, and a back smoke flue, a damper-controlled outlet in the bottom of the oven for connecting the interior of the oven with the 75 smoke flue underlying the same, a burner located in position to cause the combustion gases to enter the oven, there being an air passage extending through the rear smoke flue and communicating at its inner end 80 with the oven in proximity to the burner; and means including a device located in said passage for mixing air with gas for supplying fuel to the burner.

4. The combination with a coal range having an oven, a smoke flue underlying the oven, and a back smoke flue, a damper-controlled outlet in the bottom of the oven for connecting the interior of the oven with the 90 smoke flue underlying the same, a burner located in position to cause the combustion gases to enter the oven, there being an air passage extending through the rear smoke flue and communicating at its inner end with the oven in proximity to the burner; a closing device for the outer end of said passage; a gas controlling valve; means for simultaneously controlling said damper, said passage closing device and said gas valve; and means including a device located in said 100 passage for mixing air with gas for supplying fuel to the burner. 95

5. The combination with an oven, of opposite flues lying at opposite sides thereof and communicating with the oven through elongated slots extending from the front to the rear of the oven adjacent to the bottom of the latter, burners in said flues and having the openings therein located so as to cause the flames to extend laterally into the oven, 110 means including a device for mixing atmospheric air with gas for supplying gaseous fuel to the burners, a damper-controlled outlet for combustion gases in the bottom of the oven, and means for simultaneously controlling the admission of air to said device and 115 to said flues.

6. The combination with an oven having smoke outlets through one wall thereof, a damper arranged within the oven to control 120 said outlets and slidably along the wall of the oven in which the outlets are located, and a cleaning device lying on the opposite side of the latter wall and movable with the damper, said cleaning device having parts 125 adapted to travel across said outlet when the damper is moved and prevent soot from collecting on the discharge side of said outlets.

7. In combination with a coal range having an oven, and a smoke flue at the rear 130

thereof; an auxiliary flue lying at one side of the oven and communicating therewith through an elongated opening adjacent to the bottom of the oven; a burner in said auxiliary flue, an air passage extending through said back smoke flue and communicating with said auxiliary flue, means including an air mixing device arranged in said passage for supplying fuel to said burners, and a 10 damper controlled smoke outlet in the lower regions of the oven.

8. In combination with a coal range having an oven, and a smoke flue at the rear thereof; an auxiliary flue lying at one side of the oven and communicating therewith through an elongated opening adjacent to the bottom of the oven; a burner in said auxiliary flue, an air passage extending through said back smoke flue and communicating with said auxiliary flue, means including an air mixing device arranged in said passage for supplying fuel to said burners, and means for controlling the admission of air to said passage.

9. In combination with a coal range having an oven and a smoke flue at the rear thereof; an auxiliary flue for a burner communicating with the interior of the oven; a burner in said auxiliary flue; there being an air passage extending through the back smoke flue and communicating with said auxiliary flue; means including an air mixing device arranged in said passage for supplying fuel to said burner, and means for controlling the admission of air to said passage.

10. The combination with an oven, of chambers or flues extending along the sides

of the oven and each communicating with the interior of the oven through a long narrow opening, burners mounted in said flues in such a manner that the air passing from the flues through said openings is prevented from flowing behind and underneath the burners but must pass across the top of the latter, and a valve-controlled smoke outlet in the lower portion of the oven.

11. The combination with an oven, of chambers or flues extending along the sides of the oven and each communicating with the interior of the oven through a long narrow opening, burners mounted in said flues in such a manner that the air passing from the flues through said openings is prevented from flowing behind and underneath the burners but must pass across the top of the latter, and an elongated valve-controlled outlet in the bottom wall of the oven at a point between said flues and extending parallel therewith.

12. The combination with an oven, of an air flue extending along one side thereof in the vicinity of the bottom and communicating with the interior of the oven through a long narrow opening adjacent to the bottom of the oven, a burner lying in said flue and fitting against an adjacent wall of the latter so as to prevent air from passing behind and underneath the burner and compel it to pass across the top of the burner in flowing from the flue into the oven, and a valve-controlled smoke outlet in the lower region of the oven at a point remote from said flue.

In testimony whereof, I sign this specification.

GEORGE W. CLARK.
